UNITED STATES PATENT OFFICE.

HARRIE A. BALLARD, OF ASHLAND, MASSACHUSETTS, ASSIGNOR TO THE BOYLSTON MANUFACTURING COMPANY, OF BOSTON, MASSACHUSETTS, A CORPORATION OF NEW JERSEY.

CHAIN-STITCH SHOE-SEWING MACHINE.

No. 873,486.

Specification of Letters Patent.

Patented Dec. 10, 1907.

Application filed March 13, 1905. Serial No. 249,693.

To all whom it may concern:

Be it known that I, HARRIE A. BALLARD, of Ashland, in the county of Middlesex and State of Massachusetts, have invented certain new and useful Improvements in Chain-Stitch Shoe-Sewing Machines, of which the following is a specification.

This invention relates to chain-stitch shoe-sewing machines of either the "welt" or "turned" type, and consists of an improved thread-measuring device which may be adjusted to take thread from the supply in proportion to the length of the stitch which is being sewed, and to so measure it that the stitch shall be tight or loose or of any intermediate tension when set.

The sewing machine in connection with which the present improved thread-measuring device is shown is similar to that illustrated in my co-pending application, Serial No. 242,489, filed January 24, 1905. The hereinafter-described thread-measuring device comprises a "thread-finger" common to most machines of this type, and means for actuating the thread-finger to draw a predetermined amount of thread from the "looper" for each stitch. The thread-finger receives a back-and-forth motion from a cam provided for it, and in addition thereto it receives a lateral motion from the mechanism which feeds the work. These two motions are so timed that they produce a "four-way" motion of the thread-finger, of which the length of the lateral motion is increased or decreased as the feeding motion is increased or decreased.

An adjusting device is provided for so regulating the lateral movement of the thread-finger that the latter may be caused to draw more or less thread in proportion to the length of the stitch. It is so constructed that it may be set to cause the thread-finger to draw a maximum portion of thread for the formation of a loose stitch, or it may be set to any desired position of adjustment and thereby demand only the portion of thread necessary for a stitch of the desired tension.

Of the accompanying drawings, forming a part of this specification:—Figure 1 is a front elevation of a chain-stitch shoe-sewing machine equipped with the herein-described thread-measuring device. Fig. 2 is a front elevation of the thread-measuring device in another position. Fig. 3 is a side elevation

of the device. Fig. 4 is similar to Fig. 2, except that the device is adjusted to a different position. Figs. 5 to 9 illustrate the consecutive positions of the thread-finger during the forming of a stitch.

The same reference characters indicate the same parts, wherever they occur.

For the purpose of clearly illustrating the coöperation of the herein-described device with that of the several elements of a sewing machine,—Fig. 1 shows a complete sewing machine head into which the device is incorporated. The head comprises a frame 10 suitably mounted in a standard 11, and having a cam-shaft 12 suitably journaled therein to be rotated in the usual way. A needle 13, which is of the hooked oscillatory type, a looper 14, a thread-finger 15, and actuating mechanisms therefor constitute the sewing or stitch-forming mechanism. The needle 13 is mounted upon a stud 16 which is rigidly affixed to a movable dovetailed feeding-block 17 in laterally extending guides 18 on the frame 10. The needle is adapted to be oscillated upon the stud 16 by an eccentrically actuated rod 19 connected to an eccentric 20 keyed upon the shaft 12. The connections between the needle and the eccentric 19 are such that the needle may be moved longitudinally of its axis as well as about its axis, but the shoulder 21 and collar 22 on the stud 16 prevent axial movement of the needle relatively to the stud.

A lever 23 pivoted by a stud 24 to the frame 10 has at one end a trundle-roll 25 which occupies a cam-groove 26 in a cam-member 27 keyed to the shaft 12. The other end of the lever 23 has a substantially radial slot 28, in which is clamped a stud 29. The stud 29 projects into a vertical slot 30 formed in a plate 31 affixed to the feeding-block 17, so that as the lever is oscillated by the cam 26, the stud 29 carried by it reciprocates the feeding-block in the guides 18. By reason of the shoulder 21 and collar 22 on the rigidly-secured stud 16, the needle 13 reciprocates with the feeding-block independently of the oscillation caused by the eccentric rod 19. The lateral reciprocating motion of the needle effects the feeding of the work since the motion from right to left occurs while the needle is in the work, and the motion from left to right when the needle is disengaged from the work. The feeding movement of

the needle and consequently the length of each stitch may be varied by changing the position of the stud 29 in the slot 28. In Figs. 1 and 2, the stud 29 is shown set at the 5 position nearest the stud or fulcrum 24, and the relatively short radius between said studs effects a short motion of the feeding-block 17 and the needle. In Fig. 2, the needle and feeding-block are in full lines at the 10 leftward extreme of their movement, and the rightward extreme is indicated by dotted lines. In all cases, however, the leftward extreme remains the same so that the needle may always stop in line with the looper 14 15 for a purpose hereinafter explained. In Fig. 4, the stud 29 is set at the other extreme of the slot 30. By reason of this adjustment, the movement of the lever 23 effects a maximum movement of the feeding-block and 20 needle, as indicated by the space between the full and dotted lines, indicating the needle and right-hand end of the feeding-block.

The looper 14, of which the actuating mechanism is not illustrated in detail, is of the 25 tubular type, and is adapted to be rotated about a fixed axis. As illustrated in Fig. 1, the thread *x* is drawn through the looper and through an eccentric nozzle 32, formed at the lower end thereof. The 30 looper is rotatably mounted in a bracket 33, projecting forward from the frame 10 and is provided with a spiral gear 34 which intermeshes with a spiral gear 35 affixed to a shaft 36. The shaft 36 is suitably journaled in 35 fixed bearings and receives an intermittent rotation from a mutilated gear 37 affixed to the shaft 12. The intermittent rotation of the shaft 36 is such as to cause the eccentric nozzle 32 of the looper to describe one and 40 one-half turns to the right and one-half a turn to the left around the barb of the needle for each rotation of the shaft 12.

The description so far deals only with 45 the stitch-forming mechanism common to the machine shown and described in my said co-pending application, and the following description refers to the thread-finger or thread-measuring device which constitutes the feature of the invention.

50 As previously stated, the thread-finger, which draws the required amount of thread for each stitch from the nozzle of the looper is indicated at 15. The thread-finger 15 is pivoted at 38 to a sleeve 39 movably mounted upon a rod 40 of which the ends are held in brackets 41 41 projecting from the frame 10.

The shape of the lower end of the thread-finger is best shown in Figs. 1 and 9. A 55 backward and forward oscillation or vibrating motion is imparted to the thread-finger by a lever 42 pivoted upon the rod 40. The lever 42 has at one end a trundle-roll 43 which occupies a cam-groove 44 in the cam- 60 member 27. The other end of the lever 42

is in the form of a fork 45, which straddles a portion of the thread-finger intermediate of its ends. It is evident, therefore, that as the lever 42 is oscillated by the cam 44, that the thread-finger is oscillated backward and 70 forward on the rod or pivot 40, and in a plane parallel to the plane of oscillation of the needle. This motion of the thread-finger is common to the majority of machines of this type, but with it is combined a lateral vibrating movement which is dependent in one respect upon the length of travel of the feeding block 17. To this end the thread-finger is connected to the feeding-block 17 by an adjustable connecting device having universal 80 joints adapted to permit the first-mentioned vibration of the thread-finger relatively to the feeding-block. This connecting device comprises a stud 46 which is affixed to and projects forwardly from the feeding-block 85 17. A collar 47 is loosely mounted upon the stud 46 and has provisions for carrying a screw-threaded stem 48 to which it is pivotally connected by a pin, extending in a direction transverse to the stud 46. The screw-threaded stem 48 is threaded into a member 49 which is pivotally connected to the thread-finger 15 by a pin 50. It is evident, by reason of this connection between the thread-finger and the feeding-block, that when the feeding block is reciprocated as previously described, it imparts lateral motion to the thread-finger, and that, by reason of the connection between the thread-finger and the lever 42, the thread-finger is free to move 100 laterally with relation to the forked end 45 of said lever, and yet remain in operative relation thereto. These two motions of the thread-finger are so timed that they cause it to describe a four-way motion. The lateral 105 movement of the thread-finger and consequently the tension of the stitches may be varied by a device which changes the lateral movement from a rectilinear to an oscillating movement. This device comprises the collar 39, which, as already stated, is movably mounted upon the rod 40 and a stop-nut 51 screw-threaded upon the rod 40. The thread-finger is provided with a projection 52 near its upper end which is adapted to impinge against a collar 53 stationarily mounted upon the rod 40, between the lever 42 and the collar 39.

The function of the projection 52 and collar 53 is that of limiting the movement of the 110 thread-finger toward the right, relatively to the collar 39, as illustrated in Fig. 1. In this figure, the lower end of the thread-finger is in its forward position, which is directly under the nozzle 32 of the looper 14, (see also 115 Fig. 5). In Fig. 1, the thread-finger is also at the right extreme of its lateral motion, being held there by the feeding block 17 which is likewise at the right extreme of its motion. When the feeding-block moves to 120

this position and carries with it the thread-finger, it causes the projection 52 to impinge against the under surface of the collar 53 and collar 39 to impinge against the collar 53. It is evident, therefore, that the normal position of the thread-finger 15 is determined by the nose 52 and collar 39, which both impinge against the collar 53. When the feeding-block 17 is reciprocated to the left, to feed the work, it moves the thread-finger 15 to the left. The resistance of the thread upon the lower end of the thread-finger prevents the latter from oscillating upon the pin 38, and holds the nose 52 against the collar 53. The thread-finger and collar 39 therefore move rectilinearly as a unit until the latter is arrested by the stop-nut 51. If the stop-nut is so adjusted on the rod 40 that the collar 39 impinges against it before the completion of the stroke of the block 17, the remaining movement of the block 17 causes the lower end of the thread-finger to move at increased speed about the pivot 38. When the parts have moved to this position, they are as shown in Fig. 7.

The relative movements of the needle 13, the thread-finger 15, and the nozzle 32 are illustrated in Figs. 5 to 9. Fig. 5 shows these members in normal position, that is, previous to the first movement of forming a stitch in the work. In this figure, the needle is to the right of the looper, preparatory to being inserted in the work. Fig. 6 shows the needle after it has penetrated the work and emerged from the other side thereof, and also shows the position of the thread-finger after the rearward movement thereof caused by the lever 42. It may be here stated, that the backward and forward oscillation of the thread-finger never varies, and consequently the first movement of the thread-finger draws the same amount of thread from the looper under all conditions. After the thread-finger and needle have moved to the position shown in Fig. 6, the feeding-block 17 is reciprocated to the left, carrying with it the needle and the thread-finger. This movement carries the needle to a position in alignment with the nozzle 32 and causes the thread-finger to move in a lateral direction. In describing the second motion, the thread-finger moves to a greater distance from the nozzle of the looper, thereby drawing from the nozzle the portion of thread determined by the movement caused by the feeding-block and regulated by the stop-nut 51. The needle and thread-finger remain in the position shown in Fig. 7 during the actuation of the looper. The looper is caused to scribe $1\frac{1}{2}$ turns about the barb of the needle, as previously stated, and comes to a state of rest in the position shown in Fig. 8, after having laid the thread around the needle. The needle is then caused to recede, drawing the thread through the work and through the

previous stitch, and at the same time the thread-finger is oscillated forward by the lever 42, thereby disengaging itself from the thread, so that the thread is free to be drawn into the work by the needle. This leaves the parts in the position shown in Fig. 9. The next action is that of the feeding-block 17, which is caused to move to the right to its original position. In so doing, the feeding-block carries with it the needle and the thread-finger to their original position, as shown in Fig. 5. Fig. 2 shows the stud 29, adjusted to move the feeding-block for a short stitch, and Fig. 4 shows the stud adjusted to move the feeding-block for a long stitch. So long as the thread-finger is permitted to move rectilinearly with the feeding-block 17, the end of the thread finger which draws the thread moves only as fast as the feeding block, but when the rectilinear movement of the thread-finger is arrested by the stop-nut 51 and oscillation of the thread-finger occurs during the remainder of the stroke of the feeding block 17, the lower end of the thread-finger travels to a correspondingly increased distance.

In Figs. 1 and 2, considerable space is left between the sleeve 39 and the stop-nut 51. As a result of this adjustment, the thread-finger receives from the feeding-block 17 simply a lateral rectilinear motion equal to the motion of the block itself, inasmuch as the movement of the thread-finger is no more than enough to cause the sleeve 39 to impinge against the stop-nut 51. The thread-finger is therefore caused to draw from the looper a relatively short length of thread, and the stitch formed thereof is consequently a tight stitch. A different adjustment is shown in Fig. 4 to illustrate the position to which the parts may be set to form a loose stitch. In this figure, the stop-nut 51 is adjusted to a position closer to the sleeve 39, and as a result, the greater proportion of movement of the thread-finger is oscillation, and since the thread-engaging end of the thread-finger is moved further by oscillation than by rectilinear movement, the thread-finger draws a greater proportion of thread than it would if more freedom of movement were given to the sleeve 39.

In Fig. 4, as previously stated, the stud 29 is so adjusted as to cause a maximum motion of the feeding block. It is shown that when the feeding-block is at the left-hand position, the slot 28 in the lever 23 is parallel to the slot 30 in the plate 31, and consequently the left-hand extreme of the feeding-block is not affected by an adjustment of the stud 29, the variation in movement of the feeding-block affecting only the right-hand extreme of movement thereof.

Having thus explained the nature of the invention, and described a way of constructing and using the same, although without

attempting to set forth all the forms in which it may be made, or all of the modes of its use, I declare that what I claim is:—

- 5 1. A chain-stitch shoe-sewing machine comprising stitch-forming mechanism including a hooked needle, a looper and means for operating them, a thread-finger, work-feeding mechanism adapted to feed the work one step for each stitch, and adapted to 10 cause said thread-finger to draw from the thread supply a predetermined supply of thread through the looper for each stitch.
- 15 2. A chain-stitch shoe-sewing machine comprising stitch-forming mechanism including a hooked needle, a looper and means for operating them, a thread-finger, work-feeding mechanism adapted to feed the work one step for each stitch, means for varying the length of the steps, and means for causing 20 said thread-finger to draw from the thread-supply a supply of thread through the looper proportionate to the length of each step.
- 25 3. A chain-stitch shoe-sewing machine comprising stitch-forming mechanism including a hooked needle, a looper and means for operating them, a thread-finger, work-feeding mechanism adapted to feed the work one step for each stitch, and means actuated 30 by said work-feeding mechanism for causing said thread-finger to engage the thread between the looper and the work and to draw from the thread-supply a predetermined supply of thread for each stitch.
- 35 4. A chain-stitch shoe-sewing machine comprising stitch-forming mechanism including a hooked needle, a looper and means for operating them, a thread-finger, work-feeding mechanism adapted to feed the work 40 one step for each stitch, means for varying the length of the steps, and means actuated by said work-feeding mechanism for causing said thread-finger to engage the thread between the looper and the work and to draw 45 from the thread-supply a supply of thread for each stitch in proportion to the length of the steps.
- 50 5. A shoe-sewing machine comprising stitch-forming mechanism including a movable thread-finger adapted to engage the thread, and means for vibrating said thread-finger in a predetermined direction, work-feeding means adapted to feed the work one step for each stitch, and means actuated by 55 said work-feeding means for vibrating said thread-finger transversely of said predetermined direction.
- 60 6. A shoe-sewing machine comprising stitch-forming mechanism including a movable thread-finger adapted to engage the thread, and means for vibrating said thread-finger in a predetermined direction and to a predetermined extent, work-feeding means adapted to feed the work one step for each 65 stitch, means for varying the length of the

feeding steps, and means connecting said work-feeding means and said thread-finger whereby said work-feeding means vibrates said thread-finger to an extent proportionate to the length of said steps, and in a direction 70 transverse to said predetermined direction.

7. A shoe-sewing machine comprising a thread-finger mounted upon a universal joint and adapted to engage the thread, means for oscillating said thread-finger back 75 and forth, a reciprocating work-feeding member adapted to feed the work step-by-step, and means connecting said feeding member and said thread-finger whereby reciprocation of said feeding member oscillates said thread-finger from side to side independently of the back-and-forth oscillation thereof.

8. A shoe-sewing machine comprising 85 stitch-forming mechanism including a hooked needle, a looper and means for operating them, a movable thread-finger adapted to engage the thread between the work and the looper, and means for feeding the work and for actuating said thread-finger simultaneously.

9. A chain-stitch shoe-sewing machine comprising stitch-forming mechanism including a hooked needle, a looper and means for operating them, a movable thread-finger 95 adapted to engage the thread between the work and the looper, means for feeding the work by step-by-step movements, and for actuating said thread-finger, and means for varying the length of said movements and 100 the length of movement of said thread-finger.

10. A shoe-sewing machine comprising reciprocating work-feeding means, a thread-finger connected to said feeding means and 105 adapted to be reciprocated thereby in the same direction as said feeding means, and adapted to be moved in a plane transverse to and independently of said reciprocating movement, means for moving said thread-finger transversely of said reciprocating movement, and means for varying the length of reciprocation of said feeding means and 110 said thread-finger coincidentally.

11. A shoe-sewing machine, comprising a 115 thread-finger adapted to oscillate and to move rectilinearly, work-feeding means adapted to reciprocate said thread-finger, and means for causing the reciprocation of said thread-finger to be either oscillatory or 120 rectilinear.

12. A shoe-sewing machine comprising a thread-finger adapted to oscillate and to move rectilinearly, work-feeding means adapted to reciprocate said thread-finger, and means for causing rectilinear or oscillatory motion of said thread-finger to change 125 from one to the other.

13. A shoe-sewing machine comprising a thread-finger adapted to oscillate and to 130

move rectilinearly, work - feeding means adapted to reciprocate said thread-finger by a stroke of predetermined length, and adjustable means for causing rectilinear or oscillatory motion of said thread-finger by a stroke of predetermined length, and adjustable means for causing rectilinear or oscillatory motion of said thread-finger to change from one to the other at any desired point of said stroke.

14. A shoe-sewing machine comprising a reciprocatory member, an oscillatory thread-finger pivoted to said member, work-feeding means adapted to reciprocate said thread-finger and said member as a unit, and adjustable means for limiting the movement of said member only.

15. A shoe-sewing machine comprising a member adapted to reciprocate laterally with relation to the machine and to oscillate

in a plane transverse to the direction of reciprocation, a thread-finger pivotally connected to said member so as to oscillate laterally of the machine, work-feeding means adapted to reciprocate said thread-finger laterally, means for causing rectilinear or oscillatory motion of said thread-finger to change from one to the other, and means for oscillating said thread-finger and said member as a unit in a plane transverse to the direction of reciprocation of said member and independently of lateral movement of said thread-finger and said member.

In testimony whereof I have affixed my signature, in presence of two witnesses.
